CLAIM

The ornamental design for a baby bed, as shown and described.

DESCRIPTION

FIG. 1 is a top, front and left side perspective view of a first embodiment of a baby bed showing our new design; FIG. 2 is a bottom, rear and right side perspective view of FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged view of portion 9 in FIG. 1;

FIG. 10 is a top, front and left side perspective view of a second embodiment of the baby bed;

FIG. 11 is a bottom, rear and right side perspective view of FIG. 10;

FIG. 12 is a front elevational view of FIG. 10;

FIG. 13 is a rear elevational view of FIG. 10;

FIG. 14 is a left side view of FIG. 10;

FIG. 15 is a right side view of FIG. 10;

FIG. 16 is a top plan view of FIG. 10;

FIG. 17 is a bottom plan view of FIG. 10;

FIG. 18 is an enlarged view of portion 18 in FIG. 10;

FIG. 19 is a top, front and left side perspective view of a third embodiment of the baby bed;

FIG. 20 is a bottom, rear and right side perspective view of FIG. 19;

FIG. 21 is a front elevational view of FIG. 19;

FIG. 22 is a rear elevational view of FIG. 19;

FIG. 23 is a left side view of FIG. 19;

FIG. 24 is a right side view of FIG. 19;

FIG. 25 is a top plan view of FIG. 19;

(Continued)

FIG. 26 is a bottom plan view of FIG. 19;
 FIG. 27 is an enlarged view of portion 27 in FIG. 19;
 FIG. 28 is a top, front and left side perspective view of a fourth embodiment of the baby bed;
 FIG. 29 is a bottom, rear and right side perspective view of FIG. 28;
 FIG. 30 is a front elevational view of FIG. 28;
 FIG. 31 is a rear elevational view of FIG. 28;
 FIG. 32 is a left side view of FIG. 28;
 FIG. 33 is a right side view of FIG. 28;
 FIG. 34 is a top plan view of FIG. 28;
 FIG. 35 is a bottom plan view of FIG. 28;
 FIG. 36 is an enlarged view of portion 36 in FIG. 28;
 FIG. 37 is a top, front and left side perspective view of a fifth embodiment of the baby bed;
 FIG. 38 is a bottom, rear and right side perspective view of FIG. 37;
 FIG. 39 is a front elevational view of FIG. 37;
 FIG. 40 is a rear elevational view of FIG. 37;
 FIG. 41 is a left side view of FIG. 37;
 FIG. 42 is a right side view of FIG. 37;
 FIG. 43 is a top plan view of FIG. 37;
 FIG. 44 is a bottom plan view of FIG. 37;
 FIG. 45 is an enlarged view of portion 45 in FIG. 37;
 FIG. 46 is a top, front and left side perspective view of a sixth embodiment of the baby bed;
 FIG. 47 is a bottom, rear and right side perspective view of FIG. 46;
 FIG. 48 is a front elevational view of FIG. 46;
 FIG. 49 is a rear elevational view of FIG. 46;
 FIG. 50 is a left side view of FIG. 46;
 FIG. 51 is a right side view of FIG. 46;
 FIG. 52 is a top plan view of FIG. 46;
 FIG. 53 is a bottom plan view of FIG. 46; and,
 FIG. 54 is an enlarged view of portion 54 in FIG. 46.
